(57) **CLAIM**

The ornamental design for a firecrackers string light as shown and described.

DESCRIPTION

FIG. 1 is a front, left and top perspective view of a firecrackers string light, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The dashed broken lines depict portions of the firecrackers string light that form no part of the claimed design.

The dot-dash broken lines in FIGS. 1, 2, 9 and 10 depict the boundaries of the enlargements that form no part of the claimed design.

The firecrackers string light is shown with symbolic breaks in its length. The appearance of any portion of the article between the break lines forms no part of the claimed design.
